(57) **CLAIM**

The ornamental design for a vessel with lid, as shown and described.

DESCRIPTION

FIG. 1 is a front, left perspective view of a vessel with lid showing one embodiment of our new design;

FIG. 2 is a left side elevation view of FIG. 1;

FIG. 3 is a right side elevation view of FIG. 1;

FIG. 4 is a rear elevation view of FIG. 1;

FIG. 5 is a front elevation view of FIG. 1;

FIG. 6 is a top plan view of FIG. 1;

FIG. 7 is a bottom plan view of FIG. 1;

FIG. 8 is a rear, right perspective view of FIG. 1;

FIG. 9 is a front, left perspective view of a vessel with lid showing another embodiment of our new design;

FIG. 10 is a left side elevation view of FIG. 9;

FIG. 11 is a right side elevation view of FIG. 9;

FIG. 12 is a rear elevation view of FIG. 9;

FIG. 13 is a front elevation view of FIG. 9;

FIG. 14 is a top plan view of FIG. 9;

FIG. 15 is a bottom plan view of FIG. 9; and,

FIG. 16 is a rear, right perspective view of FIG. 9.

The dash-dot broken lines shown in the FIGS. 7 and 15 represent boundaries of the claim and form no part of the claimed design. The broken lines in the drawings depict portions of the vessel with lid that form no part of the claimed design.

1 Claim, 10 Drawing Sheets
